(57) **CLAIM**

The ornamental design for a shop light with diamond pattern, as shown and described.

DESCRIPTION

FIG. 1 is a perspective view of the top side of a shop light with diamond pattern, showing the new design;

FIG. 2 is a perspective view of the bottom side of the shop light with diamond pattern from FIG. 1;

FIG. 3 is a left, side elevational view thereof;

FIG. 4 is a right, side elevation view thereof;

FIG. 5 is a bottom view thereof;

FIG. 6 is a left end view thereof, where the right end view is identical to what is shown; and,

FIG. 7 is a top plan view thereof.

The broken lines shown in the drawings are for illustrative purposes only and form no part of the claimed design.
